UNITED STATES PATENT OFFICE.

FRANCIS P. PIDGEON, OF BROOKLYN, NEW YORK.

ENVELOP.

SPECIFICATION forming part of Letters Patent No. 722,038, dated March 3, 1903.

Application filed October 7, 1902. Serial No. 126,313. (No model.)

To all whom it may concern:

Be it known that I, FRANCIS P. PIDGEON, a citizen of the United States, and a resident of the city of New York, borough of Brooklyn, in the county of Kings and State of New York, have invented new and useful Improvements 5 in Envelops, of which the following is a full, clear, and exact description.

The object of the invention is to provide 10 certain new and useful improvements in envelopes, whereby a number of envelopes arranged in a continuous length are detachably connected with each other to allow of running the envelopes through a type-writing machine for addressing the envelopes in a 15 convenient and quick manner.

The invention consists of novel features 20 and parts and combinations of the same, as will be more fully described hereinafter, and 20 then pointed out in the claims.

A practical embodiment of the invention is 25 represented in the accompanying drawings, forming a part of this specification, in which similar characters of reference indicate corresponding parts in all the views.

Figure 1 is a rear elevation of the improvement. Fig. 2 is a transverse section of the same, and Fig. 3 is a face view of part of the blank for forming the envelopes. 30 The envelopes A, A', A², and A³ are made from a single blank of paper and arranged in a continuous length, as plainly indicated in Figs. 1 and 2, and each of the said envelopes 35 consists of a front B, side flaps C, a top or closing flap D, and a bottom flap E, of which the side flaps C and the bottom flap E are fastened together in the usual manner, and the upper edge of the top flap D is integrally connected with the upper edge of the bottom 40 flap E of an adjacent envelop. The junction between the top flap D and the bottom flap E is scored or perforated, so as to allow of conveniently detaching the top flap of one envelop from the bottom flap of the adjacent 45 envelop to separate an envelop from the continuous length of envelopes.

In making the series of envelopes described a single piece of paper is formed into a blank, (shown in Fig. 3,) and the side flaps of each

envelop-blank are folded over, together with 50 the corresponding bottom flap E, and fastened together in the usual manner, while the top flap of one envelop is loosely folded onto the bottom flap E of the adjacent envelop, so that the series of envelopes form a continuous front 55 face composed of the fronts B of the several envelopes. Now this continuous length of envelopes can be readily run through a type-writing machine to address the envelopes successively in a convenient and quick manner. 60 The envelopes addressed are readily detached one from the other along the score-line or perforation extending at the joint between the top flap of one envelop and the bottom flap of an adjacent envelop. 65

Having thus described my invention, I claim as new and desire to secure by Letters Patent—

1. A series of envelopes made from a single blank and arranged in continuous length, 70 each envelop comprising a front, side flaps adapted to be folded inward toward each other, a top or folding flap, and a bottom flap adapted to be folded inward and secured to the side flaps, the closing flap of one envelop 75 having its free end integrally connected with the upper edge of the bottom flap of an adjacent envelop and sealed to its side flaps, the construction being such that the blank may be formed into a series of envelopes without tearing or detaching any portion of such blank. 80

2. A blank for forming a series of envelopes in continuous length, comprising a plurality of fronts, side flaps on each front and top and bottom flaps on each front, the top and bottom flaps being integrally connected and so formed that a series of connected envelopes 85 may be made from the blank without separating or tearing a portion of said blank. 90

In testimony whereof I have signed my name to this specification in the presence of two subscribing witnesses.

FRANCIS P. PIDGEON.
